UNITED STATES PATENT OFFICE

ARCHIBALD G. SHAVER, OF CHICAGO, ILLINOIS, ASSIGNOR TO REGAN SAFETY DEVICES COMPANY, INC., A CORPORATION OF NEW YORK

INDUCTION-TYPE TRAIN CONTROL

Application filed November 8, 1920. Serial No. 422,598.

This invention relates to a train control system, and more particularly to a train control system of the induction type, and has special reference to the provision of an induction system arranged to be connected to and influenced by a block signalling system, with the induction system responsive to "safety", "caution" and "danger" track conditions to produce corresponding "clear", "caution" and "stop" effects on the train.

A principal object of the present invention comprehends the provision of an induction train control system in which train carried mechanism is operated to produce a plurality of effects such as proceed, speed restrictive and stop effect responsive to the cooperation between train and track magnetic elements or inductoriums with the train carried mechanism given a tripping or deenergizing operation in each section or block so as to condition the same for further operation and so as to determine the operability thereof to keep the same in proper working order at all times.

A further principal object of the invention relates to the provision of an induction train control system of the type referred to in which the train and track magnetic elements or inductoriums are operated by train carried energy.

Further objects of the invention relate to the provision of an induction train control system in which the train carried mechanism includes a pneumatic valve electrically controlled over a normally closed vehicle circuit, and employing a combined reservoir and brake valve of the type shown in my copending Patent No. 1,411,526 of April 4, 1922, in addition to a speed circuit controller similar to that shown and described in my copending application filed June 10, 1919, Serial No. 303,191, whereby the pneumatic valve, normally maintained energized when the train is moving from one point to another, continues to be energized under "clear" and "caution" conditions, but is deenergized under "danger" conditions, the said pneumatic valve being placed under the control of the speed circuit controller under "caution" conditions.

To the accomplishment of the foregoing and such other objects as may hereinafter appear, my invention consists in the elements and their relation one to the other, as herein-after particularly described and sought to be defined in the claims, references being had to the accompanying drawing which shows a preferred embodiment of my invention, and in which:—

The figure illustrates a diagrammatic view of the complete train control apparatus and the roadside apparatus, diagrammatically indicating the latter controlled by the signalling system.

Referring to the drawing, the various train circuits will be described in sequence as follows: for normally energizing the relay 9 there is provided the circuit #1 which includes the battery 1, conductors 2, 3 and 4, the circuit make and break permanent magnet 5 which under normal conditions is arranged as shown in full lines in the drawing with the south pole of the same in contact with contact 7 and against stop 6, the conductor 8, the relay 9, and conductors 10 and 11. This circuit is normally maintained closed as shown, the permanent magnet 5 being held in its circuit closing position by means of the soft iron piece *a* which functions as a stabilizing means for holding the permanent magnet in such circuit closing position when the same is actuated to such position by means hereinafter to be described.

For normally energizing the relay 16 there is provided the circuit #2 which includes the battery 1, conductors 2 and 3, the circuit make and break permanent magnet 12 having the south pole held against the stop 13 and contact 14 as indicated in full lines in the figure, conductor 15, relay 16, and conductor 11. The permanent magnet 12 is held in its circuit closing position for normally maintaining the circuit closed by means of the soft iron piece *a'* which functions as a stabilizing means for holding the permanent magnet in its full line or circuit closing position when the same is actuated to such position by means also hereinafter to be described.

When circuits 1 and 2 are closed, energizing the relays 9 and 16 respectively, (this cor-

responding to "safe" track conditions,) a circuit #3 is established for energizing the magnet 24 of a combined reservoir and brake valve 26 which is of the construction as shown in my copending Patent No. 1,411,526 of April 4, 1922, and which comprises the train or vehicle controlling mechanism. This circuit includes the battery 1, conductors 2 and 17, contact finger 18, contact 19, conductor 20, contact finger 21, contact 22, conductors 31 and 23, electromagnet 24, and conductors 25 and 11. The combined reservoir and brake valve 26 includes, as set forth in my copending patent, the pipe 27 leading from the main reservoir, the pipe 28 normally communicating therewith and leading to the engineer's brake valve, the pipe 29 leading from the train pipe of the air brake system, and vent pipe 30 connected to but normally out of communication with the train pipe 29, these parts being under the control of the magnet 24 which is normally energized under "safe" conditions. The construction is such that deenergization of magnet 24 cuts off communication of air from the main reservoir to the engineer's brake valve by disconnecting the pipe 28 from the pipe 27 and vents the train pipe 29 through vent pipe 30 by effecting communication therebetween.

Under roadside "safety" conditions, in addition to the closing of circuit #3, the clear light G is energized by a circuit #4 which is closed as follows: battery 1, the conductors 2 and 17, the contact finger 18, the contact 19, the conductor 20, the contact finger 21, the contact 22, the conductor 31, the clear light G, and the conductors 32 and 11.

Under "caution" track conditions, the circuit #1 is opened and the circuit #2 is closed, as will be described hereinafter, resulting in the deenergization of the relay 9 and the energization of the relay 16, and under these conditions the "caution" light 40 is energized by a circuit #5 which includes: the battery 1, the conductors 2 and 33, the contact finger 34, the back contact 35, the conductor 36, the contact finger 37, the contact 38, the conductor 39, "caution" light 40, and conductors 32 and 11.

Under these "caution" track conditions a circuit #6 which includes a speed circuit controller 45 is closed, the said circuit including the battery 1, the conductors 2 and 33, the contact finger 34, the back contact 35, the conductor 36, the conductor 41, the contact finger 42, the contact 43, the conductor 44, speed controller 45, the conductors 46 and 23, the electromagnet 24, and the conductors 25 and 11, the speed circuit controller being thus placed in circuit and more specifically in series with the train control magnet 24.

Under "danger" track conditions, both the electromagnets 9 and 16 are deenergized by the opening of the circuits #1 and #2, as will appear hereinafter, and then the follow-

ing circuit #7 for energizing the "danger" lamp R is energized: the battery 1, conductors 2 and 33, the contact finger 34, the back contact 35, the conductor 36, the contact finger 37, the back contact 37', the conductor 32', the danger light R and the conductors 32 and 11.

Under such "danger" track conditions by the deenergization of the magnets 9 and 16 the train control magnet 24 is deenergized, the two circuits #3 and #6 to said electromagnet 24 being open at contact 22 and contact 43, when the contact fingers 21 and 42 are released or opened, the deenergization of the magnet 24 producing "stop" effects on the train as hereinabove referred to by venting the train pipe 29 and disconnecting the engineer's brake valve from the main reservoir through pipes 28 and 27.

With the construction of this train carried mechanism and these circuits, it will be seen that by operating the circuits to energize the magnet 24, to energize the same under the control of the speed controller 45, and to deenergize the same, that proceed, speed restrictive and stop effects respectively may be produced on the train controlling mechanism.

For operating and controlling the train circuits, I provide cooperating vehicle and roadside magnetic means or elements, and more specifically vehicle and roadside inductoriums, the roadside inductoriums being preferably under the control of a block signalling system and being influenced by the same to respond to "safe", "caution" and "danger" track conditions and to indicate such conditions, and the vehicle inductoriums being arranged for movement over the roadside inductoriums and to cooperate with the latter to transmit the indications of the same to the train circuits to correspondingly influence and operate the same. To these ends, I provide a train transmitting inductorium 60 connected to the vehicle source of energy 1 by means of the conductors 59 and 61, and a train receiving inductorium 62 connected in circuit with coils 64 and 67, the coil 64 being connected to the inductorium by means of the conductors 63 and 65, and the coil 67 being connected in parallel with the coil 64 by means of the conductors 66 and 68. The coils 64 and 67 are wound so that the polarities of the coils when energized are opposite, this being shown in the figure, wherein the coil 64 is shown with the north pole at the bottom end and with the south pole at the top end, and the coil 67 with the south pole at the bottom end and the north pole at the top end when energized under "safe" track conditions.

Cooperating with the train inductoriums 60 and 62, there are provided sets of track inductoriums arranged in spaced relation along the roadside, one set for each section or block, one of such sets being shown in the drawings and comprising the receiving inductorium 60' arranged for cooperation

with the train transmitting inductorium 60 and the transmitting inductorium 62' arranged for cooperation with the train receiving inductorium 62. With this construction, it will be seen that in the movement of the train and in the passage of the train inductoriums over the track inductoriums, an impulse will be transmitted from the train transmitting inductorium 60 to the track receiving inductorium 60', and that such impulse may be transmitted, modified or inhibited for influencing the track inductorium 62' for in turn influencing the train receiving inductorium 62 to operate the coils 64 and 67 in a predetermined manner.

The interrelation between the track inductoriums 60' and 62' for transmitting, modifying or inhibiting the impulse received by the inductorium 60' is controlled by the roadside signalling apparatus, and in the present arrangement this interrelation is so controlled as to be responsive to "safe", "caution" and "danger" conditions, the construction being preferably such that under "safe" conditions the impulse will be transmitted to the inductorium 62' in one direction, under "caution" conditions such impulse will be transmitted in an opposite direction, and under "danger" conditions such impulse will be inhibited. For controlling this interrelation, there is provided a circuit changing and make and break means under the influence of the distant control relay D and the home or stop control relay H respectively.

The circuit changing means under the control of the distant or "caution" relay D comprises a pole changer including the contact fingers 66 and 67 which when the relay D is energized connect the inductoriums 60' and 62' by way of the conductor 70, the contact 71, the contact finger 67, contact finger 68, the coil of the inductorium 62', the conductor

72, the contact finger 66, the contact 73, and conductors 74 and 75. When the relay D is deenergized, the circuit connections between the inductoriums 60' and 62' are reversed, the inductoriums being connected by the circuit including the conductor 70, the contact 76, the contact arm 66, conductor 72, the coil of the inductorium 62', contact finger 68, contact finger 67, contact 77, and conductor 75. Upon deenergization of the home relay H, the contact finger 68 is opened, thus breaking the circuit between the inductoriums 60' and 62'. With this construction, it will therefore be seen that under "safe" track conditions, with the home and distant relays H and D energized, an impulse received by the inductorium 60' will be transmitted in a given direction to the inductorium 62'. It will further be seen that when the relay D is deenergized responsive to "caution" track conditions, the impulse received by the inductorium 60' will be transmitted in a reverse direction to the inductorium 62'.

When, furthermore, the relays D and H are both deenergized responsive to "danger" track conditions, the circuit will be broken and no impulse will be transmitted to the inductorium 62'.

For the purpose of conditioning the vehicle carried mechanism for operation by the train and track inductoriums so that the train circuits are made to respond to the indications of the track inductoriums, and for the further purpose of automatically giving the train control apparatus a test operation in each block in order to automatically check the operability of the same at all times, there is provided for each block a track magnet M which preferably comprises a permanent magnet having the poles arranged as indicated in the figure with the south pole uppermost, the construction and arrangement being such that the make and break train magnets 5 and 12 come under the influence of the permanent magnet M in the movement of the train thereover, such that the north poles of the make and break magnets are attracted by the south pole of the permanent magnet M, and the south pole of the make and break magnets are repelled by the south pole of the permanent magnet M, causing the make and break magnets 5 and 12 which are pivoted at their centers to rotate away from the stops 6 and 13 respectively, thus opening the circuits #1 and #2 respectively at the contacts 7 and 14 so that the relays 9 and 16 are deenergized, the make and break magnets 5 and 12 being moved by this means to their deflected dotted line positions as shown in the figure. The magnets 5 and 12 when moved to the deflected positions are held in such positions by means of the soft pieces of iron b and b' respectively, the said iron pieces functioning as stabilizing means to this end.

The track permanent magnet M is positioned along the roadside relatively to the track inductoriums 60' and 62' in such a manner that immediately after the make and break magnets 5 and 12 have come under the influence of the same the train inductoriums 60 and 62 will cover the roadside inductoriums 60' and 62' respectively, the arrangement being such that the time interval between the opening of the circuits #1 and #2 by the deflection of the magnets 5 and 12 and the control of these magnets by the cooperation of the train and track inductoriums will be too short for the train controlling mechanism to apply the brakes.

With this construction, it will be seen that in the movement of the train on the roadway, the make and break magnets 5 and 12 are periodically influenced by the spaced roadside magnets M to open the train circuits #1 and #2, the said train circuits being thus tripped and conditioned for subsequent operation by the train and track inductoriums. The train

and track inductoriums, operable in response to track conditions, then determine the further state of operation of such circuits, the inductoriums being operative to translate or transmit such track conditions for producing corresponding train effects as follows:

Under "safe" track conditions, the impulse transmitted to the train receiving inductorium 62 will energize the coils 64 and 67 to produce the polarities therein as shown in the drawing, energization of the coil 67 causing the movement of the magnet 5 from the deflected position to the horizontal circuit closing position, the south pole of the coil 67 attracting the north pole and repelling the south pole of the magnet 5, the movement of the said magnet to its circuit closing position effecting the energization of the relay 9 and the closing of the circuit #1. This impulse transmitted to the inductorium 62 will energize the coil 64 to produce the polarity as shown in the figure, the magnet 12 not being changeably influenced by this energization and being therefore maintained in its deflected position. However, the closing of the circuit #1 energizing the relay 9 has the effect of closing another train circuit which includes the battery 1, the conductor 2, the conductor 47, contact finger 48, contact 49, conductor 50, contact finger 51, contact 52, conductor 53, a coil 54 arranged adjacent to the magnet 12, conductor 55, and conductor 11. The coil 54 is so wound that when energized the north pole will be arranged adjacent to the south pole of the magnet 12, this arrangement being obviously such that upon energization of the coil 54, the permanent magnet 12 will be rotated from its deflected position to its horizontal circuit closing position. In the movement of the train, this action takes place at a moment subsequent to the time of cooperation between the train and track inductoriums and the momentary energization of coil 64 during such cooperation will permit the operation of the magnet 12 by the energized coil 54. When the magnet 12 is moved to its circuit closing position in this manner, circuit #2 is closed, energizing the relay 16, the energizing of both relays 9 and 16 effecting the closing of circuits #3 and #4 hereinbefore described for producing the "proceed" effect on the train control magnet 24 and for energizing the clear lamp G. When the relay 16 is energized by the means described, it will be seen that the contact finger 51 is raised or opened, breaking the circuit to the coil 54 so that the magnet 12 is thereafter uninfluenced thereby and is held in its circuit closing position by means of the stabilizing iron piece a' only. It will be seen, moreover, that under these conditions the magnet 5 is held in its circuit closing position by means of the stabilizing iron piece a only, so that these magnets will be in a condition to be deflected in the passage of the train over the magnet M of the succeeding block.

Under "caution" track conditions, the impulse transmitted to the train receiving inductorium 62 will energize the coils 64 and 67 in a reverse manner, with the south pole of coil 64 adjacent the magnet 12 and with the north pole of coil 67 adjacent the magnet 5. Under these conditions, the magnet 5 will remain deflected and the magnet 12 will be influenced and moved to its circuit closing position, with the result that circuit #1 remains open and relay 9 is deenergized and circuit #2 is closed, energizing the relay 16. As hereinbefore referred to, when the train circuits 1 and 2 are operated in this manner, circuits #5 and #6 are closed, placing the electro-magnet 24 in circuit with the speed controller 45 and energizing the "caution" lamp 40. With the production of this train effect, the train may proceed at limited or restricted speed and when the train exceeds such speed the magnet 24 is deenergized for producing an application of the brakes. The speed controller 45 is so constructed as to accomplish these results, the contact of the speed controller remaining closed so long as the train is proceeding at a rate not exceeding its predetermined restricted speed, and opening when this speed is exceeded, thus breaking the circuit to the magnet 24. The contact of the speed controller 45 is adjustable, and can be arranged according to heavy or light traffic. After the brakes have been applied under "caution" conditions, as when the train exceeds a predetermined speed, the speed circuit controller automatically functions to close the circuit and reenergize the electro-magnet 24 the instant the speed has been reduced to the predetermined point, the vent valve being closed and the reservoir valve opened, so that the engineer can take control of the train to proceed under such predetermined speed.

Under "danger" track conditions, no impulse will be transmitted to the inductorium 62, and the coils 64 and 67 will therefore be unenergized and the magnets 12 and 5 will remain in deflected position. Under these conditions the train circuits #1 and #2 will remain open with relays 9 and 16 deenergized, this resulting in the closing of the train circuit #7 for energizing the danger lamp R, and the opening of the train circuits #3 and #6, the said circuits being opened at contact 22 and contact 43, resulting in the deenergization of the electromagnet 24 and the production of "stop" effects on the train.

From the foregoing it will be seen that under all track conditions, the train and track inductoriums operate to determine the state or condition of operation of the magnets 5 and 12 after the same are moved to circuit opening positions by the magnet M.

After the train receives a danger track in-

dition, in order to re-establish the train circuits for producing caution effects, resetting means operable by the engineer is provided, the said resetting means comprising a manually operable push key or switch 56 disposed in a circuit including the battery 1, conductor 2, contact 58, conductor 57, conductor 53, coil 54, and conductors 55 and 11. Upon operating the switch or push key 56 to close this circuit, the coil 54 is energized and the magnet 12 is moved to its circuit closing position for energizing the relay 16, and as heretofore referred to, upon energization of the relay 16, the train circuit #6 is established for energizing the electromagnet 24 and placing the same under the control of the speed controller 45.

The permanent magnet M is preferably arranged in a roadside circuit including the distant control relay D' of the next preceding block, this circuit including the conductor 101 which has its origin at the station where the control relay D is located, the coil C wound around the permanent magnet M, the conductor 102 connected to the relay D' of the next preceding block, and the conductor 103, the arrangement being such that the current for energizing the distant control relay D' will be in a direction to increase or assist the magnetism of the permanent magnet M. Furthermore, the arrangement of coil C on the permanent magnet M is such that should the permanent magnet M become misplaced or moved, the coil C will be broken out of the circuit of which conductors 101 and 102 are a part, so that the relay D' will become de-energized, and thus an approaching train to the next preceding station will receive a "caution" control indicating a defect in the mechanism of the block ahead.

The operation of my train control system will in the main be fully apparent from the above detailed description thereof. It will be apparent that upon passage of a train over the track controlling mechanism, the train circuits will be periodically conditioned for operation and control by the track circuits, and that the train circuits will be given a test operation in each block to determine the operability thereof and to keep the same in good condition. It will be further apparent that periodically and in each block the track inductoriums 60' and 62' will respond to three roadside conditions, namely "safe", "caution" and "danger" conditions, to produce like indications therein, and that the train inductoriums 60 and 62 will cooperate with the roadside inductoriums to transmit or translate such indications to produce corresponding proceed, speed restrictive and stop effects on the train.

While I have shown my device in the preferred form, it will be apparent that many changes and modifications may be made in the structure disclosed, without departing

from the spirit of the invention, defined in the following claims.

What I claim as new is:

1. In a train control system, in combination, vehicle carried mechanism including circuit changing means, electrical provisions for controlling the operation of the same, a normally closed circuit for said provisions including a circuit make and break device, means for operating said make and break device at predetermined periods in the movement of the vehicle for operating the said provisions, and independent means operable in response to track conditions at substantially said predetermined periods for determining the further state of operation of said make and break device. 70

2. In a train control system, in combination, vehicle carried mechanism including circuit changing means, electrical provisions for controlling the operation of the same, a circuit for said provisions including a circuit make and break device, magnetic means for actuating said make and break device at predetermined periods in the movement of the vehicle for operating the said provisions, and independent magnetic means operable in response to track conditions at substantially said predetermined periods for determining the further state of operation of said make and break device. 80

3. In a train control system, in combination, vehicle carried mechanism including circuit changing means, electrical provisions for controlling the operation of the same, a circuit for said provisions including a circuit make and break device, a plurality of magnetic elements spaced at intervals along the roadside for actuating said make and break device at predetermined periods in the movement of the vehicle for operating the said provisions, and independent magnetic means operable in response to track conditions at substantially said predetermined periods for determining the further state of operation of said make and break device. 90

4. In a train control system, in combination, electrically operated vehicle control mechanism, an operating circuit therefor, electrical provisions operative for changing connections in said circuit, a circuit for said provisions including a make and break device, means for actuating said make and break device at predetermined periods in the movement of the vehicle for operating the provisions, and independent means operable in response to track conditions at substantially said predetermined periods for determining the further state of operation of said make and break device. 100

5. In a train control mechanism, in combination, vehicle carried provisions including a normally closed circuit, a circuit make and break device therefor, roadside means for directly actuating said make and break device 110

at predetermined periods in the movement of the vehicle for operating said provisions, and independent means operable in response to track conditions at substantially said predetermined periods for determining the further state of operation of said make and break device.

6. In a train control mechanism, in combination, vehicle carried provisions including a normally closed circuit, a circuit make and break device therefor, roadside magnetic means for actuating said make and break device at predetermined periods in the movement of the vehicle for operating said provisions, and independent magnetic means operable in response to track conditions at substantially said predetermined periods for determining the further state of operation of said make and break device.

7. In an inductive train control system, vehicle carried train control mechanism, means for periodically influencing the same in the movement of the vehicle on a roadway, means for periodically determining the further state of operation of the same when so influenced comprising vehicle impulse transmitting and receiving inductoriums, a source of energy therefor, and cooperating track impulse receiving and transmitting inductoriums.

8. In an inductive train control system, vehicle carried train control mechanism, magnetic means for periodically influencing the same in the movement of the vehicle on the roadway, means for periodically determining the further state of operation of the same when so influenced comprising vehicle impulse transmitting and receiving inductoriums, a source of energy therefor, and cooperating track impulse receiving and transmitting inductoriums.

9. In a train control system, vehicle carried mechanism, means including roadside mechanism for influencing the same in the movement of the vehicle over a roadway, and means for determining the operation of the same when so influenced including cooperating vehicle and roadside magnetic elements, and a vehicle source of energy for energizing the vehicle magnetic element by way of the roadside magnetic element.

10. In a train control system, vehicle carried mechanism, means including magnetic roadside mechanism for periodically influencing the same in the movement of the vehicle over a roadway, and means for determining state of the operation of the same when so influenced including cooperating vehicle and roadside magnetic elements, and a vehicle source of energy for energizing the vehicle magnetic element by way of the roadside magnetic element.

11. In a train control system, vehicle carried mechanism, means comprising roadside mechanism for influencing the same in the

movement of the vehicle to produce a tripping effect therein, and means for determining the state of operation thereof substantially when the same is tripped including cooperative vehicle and roadside magnetic elements and a vehicle source of energy for operating the said magnetic elements.

12. In an inductive train control system, vehicle carried mechanism, means comprising magnetic roadside mechanism for periodically influencing the same in the movement of the vehicle to produce a tripping effect therein, and means for periodically determining the state of operation thereof substantially when the same is tripped including cooperative vehicle and roadside magnetic elements and a vehicle source of energy for operating the said magnetic elements.

13. In an induction train control system, vehicle carried mechanism including a normally closed operating circuit, means comprising roadside mechanism for opening the circuit in the movement of the vehicle, and means for determining the further state of operation thereof including cooperating vehicle and roadside magnetic elements and a vehicle source of energy for operating the magnetic elements.

14. In an induction train control system, vehicle carried mechanism including a normally closed operating circuit, a vehicle source of energy therefor, means comprising roadside mechanism for opening the circuit in the movement of the vehicle, and means for determining the further state of operation thereof including cooperating vehicle and roadside magnetic elements connected for operation by said source of energy.

15. In an inductive train control system, vehicle carried mechanism including a normally closed operating circuit, a vehicle source of energy therefor, means comprising roadside mechanism for opening the circuit in the movement of the vehicle, and means for determining the further state of operation thereof substantially when so influenced including vehicle impulse transmitting and receiving inductoriums and track impulse receiving and transmitting inductoriums cooperating therewith, the inductoriums being connected for operation by said source of energy.

16. In an inductive train control system, vehicle carried mechanism, means including roadside mechanism for influencing the same in the movement of the vehicle to produce a predetermined effect therein, means operable substantially when the same is so influenced for modifying the effect under given track conditions to produce a different effect therein, the latter means comprising cooperative vehicle and roadside magnetic elements, and

a vehicle source of energy for operating the same.

17. In an inductive train control system, vehicle carried mechanism, means including roadside mechanism for influencing the same in the movement of the vehicle to produce a "danger" effect therein, means operable when the same is so influenced for differently modifying the effect under "safe" and "caution" track conditions to produce proceed and speed restrictive effects therein, the latter means comprising cooperative vehicle and roadside magnetic elements, and a vehicle source of energy for operating the same.

18. In an inductive train control system, vehicle carried mechanism, means including roadside mechanism for influencing the same in the movement of the vehicle to produce a "danger" effect therein, means operable when the same is so influenced for modifying the effect under "safe" track conditions to produce a proceed effect therein, the latter means comprising cooperative vehicle and roadside magnetic elements, block signalling elements for controlling the same, and a vehicle source of energy for operating the same.

19. In a train control system, vehicle carried mechanism, means including roadside mechanism for influencing the same in the movement of the vehicle over a roadway, and means for determining the operation of the same when so influenced including cooperating vehicle and roadside magnetic elements, block signalling elements for controlling the same, and a vehicle source of energy for energizing the vehicle magnetic element by way of the roadside magnetic element.

20. In an inductive train control system, vehicle carried mechanism, means including roadside mechanism for influencing the same in the movement of the vehicle to produce a "danger" effect therein, magnetic means operable substantially when the same is so influenced for modifying the effect under "safe" track conditions to produce a proceed effect therein, the latter means comprising cooperative vehicle and roadside magnetic elements, and a vehicle source of energy for operating the same.

21. In an induction train control system, vehicle carried mechanism, means including roadside mechanism for influencing the same in the movement of the vehicle to produce a "danger" effect therein, means operable substantially when the same is so influenced for modifying the effect under "safe" and "caution" track conditions to produce "safe" and "caution" effects, the latter means comprising vehicle transmitting and receiving inducto-riums, track receiving and transmitting inducto-riums cooperating therewith, a vehicle source of energy for generating impulses in said track receiving inductorium for transmission to the track transmitting inductorium

in the movement of the vehicle, and roadside means operable in response to track conditions for governing the characteristic of the impulse transmitted to the track transmitting inductorium.

22. The inductive train control system of claim 21 in which the roadside means operable in response to track conditions comprises a pole changer for reversing the direction of the transmitted impulse.

23. The inductive train control system of claim 21 in which the roadside means operable in response to track conditions comprises a pole changer for reversing the direction of the transmitted impulse and a make and break device for inhibiting the transmission of the impulse.

24. In a train control system, vehicle carried mechanism including a train controlling means and a speed controller, means including roadside mechanism for influencing the train controlling means in the movement of the vehicle, means for determining the operation of the same when so influenced including cooperating vehicle and roadside magnetic elements operable in response to track conditions, a vehicle source of energy for operating the magnetic elements, and provisions for placing the train control means under the control of the speed controller when the magnetic elements cooperate under "cautionary" track conditions.

25. In a train control system, vehicle carried mechanism including a train controlling means and a speed controller, means including roadside mechanism for influencing the train controlling means in the movement of the vehicle, means for determining the operation of the same when so influenced including a vehicle inductorium, a roadside inductorium for transmitting an impulse to said vehicle inductorium, means for governing the characteristic of the impulse so transmitted, and provisions for placing the train control means under the control of the speed controller, under a given characteristic of transmitted impulse.

26. In a train control system, vehicle carried mechanism including a train controlling means and a speed controller, means including roadside mechanism for influencing the train controlling means in the movement of the vehicle, to initiate a "danger" effect therein, means operable substantially when the same is so influenced for modifying the effect under "safe" and "caution" track conditions to produce proceed and speed restrictive effects therein, the latter means comprising cooperative vehicle and roadside magnetic elements, and provisions for placing the train controlling means under the control of the speed controller when the magnetic elements cooperate in response to "caution" track conditions.

27. In a train control system, vehicle car-

- ried mechanism including a train controlling means and a speed controller, means including roadside mechanism for influencing the train controlling means in the movement of the vehicle to initiate a "danger" effect therein, means operable substantially when the same is so influenced for modifying the effect under "safe" and "caution" track conditions to produce proceed and speed restrictive effects therein, the latter means comprising a vehicle inductorium, a roadside inductorium for transmitting an impulse thereto, means responsive to "safe" and "caution" track conditions for governing the characteristic of the impulse so transmitted; and provisions for placing the train controlling means under the control of the speed controller when the impulse transmitted corresponds to a "caution" track condition.
28. In an inductive train control system, vehicle carried mechanism and provisions for controlling the same, said provisions including an impulse transmitting roadside inductorium, an impulse receiving vehicle inductorium, means including a vehicle source of energy for producing an impulse in said roadside inductorium, and roadside means for governing the direction of flow of said impulse to said roadside inductorium.
29. In an inductive train control system, vehicle carried mechanism and provisions for controlling the same, said provisions including an impulse transmitting roadside inductorium, an impulse receiving vehicle inductorium, means including a source of energy for producing an impulse for transmission to said roadside inductorium, and roadside means operative for transmitting, modifying and inhibiting the transmission of such impulse.
30. In an inductive train control system, vehicle carried mechanism and provisions for controlling the same, said provisions including an impulse transmitting roadside inductorium, an impulse receiving vehicle inductorium, means including a vehicle source of energy for producing an impulse for transmission to said roadside inductorium, and roadside means operative for transmitting, modifying and inhibiting the transmission of such impulse.
31. In an inductive train control system, vehicle carried mechanism and provisions for controlling the same, said provisions including an impulse transmitting roadside inductorium, an impulse receiving vehicle inductorium, means including a vehicle source of energy for producing an impulse for transmission to said roadside inductorium, and roadside means operative for transmitting, modifying and inhibiting the transmission of such impulse, said roadside means including a pole changer and a make and break device.
32. In an inductive train control system, vehicle carried mechanism and provisions for controlling the same, said provisions including an impulse transmitting roadside inductorium, an impulse receiving vehicle inductorium, means including a vehicle source of energy for producing an impulse for transmission to said roadside inductorium, and roadside means operative for transmitting, modifying and inhibiting the transmission of such impulse, said roadside means including a pole changer, and a make and break device, and instrumentalities for controlling the same from a roadside signalling system.
33. In an induction train control system, vehicle carried mechanism and provisions for controlling the same, the said provisions including roadside receiving and transmitting inductoriums, vehicle transmitting and receiving inductoriums, a vehicle source of energy therefor, and means for connecting the roadside inductoriums operative to reverse circuit connections therebetween.
34. In an induction train control system, vehicle carried mechanism and provisions for controlling the same, the said provisions including roadside receiving and transmitting inductoriums, vehicle transmitting and receiving inductoriums, a vehicle source of energy therefor, and means for connecting the roadside inductoriums operative to reverse circuit connections and for breaking circuit connections therebetween.
35. In an induction train control system, vehicle carried mechanism and provisions for controlling the same, the said provisions including roadside receiving and transmitting inductoriums, vehicle transmitting and receiving inductoriums, a vehicle source of energy therefor, and means for connecting the roadside inductoriums operative to reverse circuit connections therebetween, the said means comprising a pole changer and a make and break device under the control of a roadside signalling system.
36. In an inductive train control system, vehicle carried means and provisions for controlling the same to produce "safe", "caution" and "danger" effects therein including a roadside inductorium system, a vehicle inductorium system cooperating therewith, a vehicle source of energy for energizing the inductorium systems, and roadside mechanism for controlling the same to respond to "safe", "caution" and "danger" track conditions.
37. In an inductive train control system, vehicle carried means and provisions for controlling the same to produce "safe", "caution" and "danger" effects therein including a roadside inductorium system, a vehicle inductorium system cooperating therewith, a vehicle source of energy for energizing the inductorium systems, and roadside mechanism for controlling the same to respond to "safe", "caution" and "danger" track conditions, said roadside mechanism including

a circuit changer and a make and break device.

38. In an inductive train control system, vehicle carried mechanism and provisions for

5 controlling the same including a pair of roadside inductoriums, a pair of vehicle inductoriums arranged to cooperate simultaneously with the roadside inductoriums, a vehicle source of energy for said inductoriums, roadside means operable in response to track conditions for connecting the roadside inductoriums in circuit under a "safety" track condition and operative to disconnect the same under a "warning" track condition.

15 39. In an inductive train control system, vehicle carried mechanism and provisions for controlling the same including a pair of roadside inductoriums, a pair of vehicle inductoriums arranged to cooperate simultaneously with the roadside inductoriums, a vehicle carried source of energy for said inductoriums, roadside means for connecting and disconnecting the roadside inductoriums, and roadside signalling means controlling the 20 same for effecting connection under a "safety" condition and for effecting disconnection under a "warning" condition.

25 40. In a train control system, vehicle carried means operative to produce a predetermined effect, roadside means for producing such effect, and means for modifying such effect including a vehicle carried impulse receiving inductor, a roadside impulse transmitting inductor with which said receiver is cooperable substantially when such effect is produced, and a source of electrical energy on the vehicle for energizing the transmitting inductor.

30 41. In a train control system, vehicle carried mechanism, means for governing the same including a circuit make and break device, vehicle carried stabilizing means for normally holding the make and break device in circuit making position, and means for 35 moving the same to circuit breaking position comprising roadside controlling means momentarily active in the movement of the vehicle and active in opposition to said stabilizing means; and provisions for restoring the said device to circuit making position also active momentarily in the movement of the vehicle.

35 42. In a train control system, vehicle carried mechanism, means for governing the same including a circuit make and break device, vehicle carried stabilizing means for normally holding the make and break device in circuit making position, and means for moving the same to circuit breaking position 40 comprising roadside controlling means momentarily active in the movement of the vehicle and active in opposition to said stabilizing means, stabilizing means for holding the said device in circuit breaking position, and provisions for restoring the device to cir-

cuit making position operable momentarily in the movement of the vehicle and active in opposition to said second mentioned stabilizing means.

43. In a train control system, vehicle carried mechanism and roadside mechanism controlling the same, said roadside mechanism including spaced permanent magnets one arranged in each track section or block and block signalling elements having a circuit for each block, said circuit including an energizing coil for the magnet of said block, the signalling circuit associated with the magnet of one block being arranged to produce signal indications in a preceding block.

70 44. In an inductive train control system, vehicle carried mechanism, means including roadside mechanism for influencing the same in the movement of the vehicle to produce a given effect therein under a given track condition, means operable substantially when the same is so influenced for producing either of two other effects therein under either of two other track conditions, the latter means comprising cooperative vehicle and roadside magnetic elements and a vehicle source of energy for operating the same.

75 45. In an inductive train control system, vehicle carried mechanism, means including magnetic roadside mechanism for influencing the same in the movement of the vehicle to produce a given effect therein under a given track condition, means operable substantially when the same is so influenced for producing either of two other effects therein under either of two other track conditions, the latter means comprising cooperative vehicle and roadside magnetic elements and a vehicle source of energy for operating the same.

80 46. In an induction train control system, vehicle carried mechanism, means including roadside mechanism for influencing the same in the movement of the vehicle to produce a given effect therein under a given track condition, and means operable substantially when the same is so influenced for producing either of two other effects therein under either of two other track conditions, the latter means comprising vehicle transmitting and receiving inductoriums, track receiving and transmitting inductoriums cooperating therewith, a vehicle source of energy for generating an impulse in said track receiving inductorium for transmission to the track transmitting inductorium in the movement of the vehicle, and roadside means operable in response to track conditions for governing the characteristic of the impulse transmitted to the track transmitting inductorium.

85 47. In a train control system, the combination with a roadside magnetic element and a roadside inductorium, means for controlling the flow of induced current through said inductorium, a relay carried by a moving vehicle, a source of electrical energy for con-

trolling the same, train controlling means under the operation of the relay, a magnetic switch normally holding the circuit with the relay closed and adapted to be opened when 5 passing over the roadside magnetic element, and a vehicle carried inductorium disposed to control the said magnetic switch to return the same to closed position when passing in inductive relation to the roadside inductorium. 10

48. In a train control system, the combination with a roadside magnetic element and a roadside inductorium, means for controlling the flow of induced current through 15 said inductorium, a relay carried by a moving vehicle, a source of electrical energy for controlling the same, train controlling means under the operation of the relay, a magnetic switch normally holding the circuit with the 20 relay closed and adapted to be opened when passing over the roadside magnetic element, a coil disposed in inductive relation to the magnetic switch, and an inductorium in circuit therewith and disposed to pass in inductive relation with the roadside inductorium after said switch has been moved by the first 25 inductorium to reset the said switch into closed position.

49. In a train control system, the combination of a permanent magnet disposed along the roadside, two electromagnets also disposed along the roadside and connected in circuit with each other, roadside means for controlling the direction of flow of induced 30 current from one of the latter to the other, roadside means for opening the circuit between the two electromagnets, vehicle carried means including train controlling means, a control circuit therefor including a source 35 of electrical energy, a magnetically controlled switch for the control circuit, said switch adapted to be moved to open position when passing the permanent magnet, and two electromagnets, one in circuit with the source of 40 electrical energy and the other in circuit to control the magnetic switch, whereby when the two last mentioned electro-magnets pass in inductive relation to the roadside electromagnets the magnetic switch will be controlled thereby relative to the direction of 45 flow of the induced current from the source of electrical energy of the vehicle through all of the electromagnets. 50

50. In a train control system, the combination with a permanent roadside magnet, two electromagnets connected in a partial circuit and disposed along the roadside, pole changing means in said circuit controlled from the roadside means for permitting a reversal of 55 flow of induced current in said partial circuit, a vehicle carried source of electrical energy, two relays in circuit therewith, train controlling means under the influence of said cab relays, two magnetic switches normally 60 closed for controlling the respective relays, 65

said switches being adapted to be opened when passing the permanent magnet, two electromagnets, one in circuit with the source of electrical energy and both disposed to pass in inductive relation to the roadside electromagnets whereby an induced current is transmitted from the electromagnet connected with the source of electrical energy through the roadside electromagnets to the remaining vehicle electromagnet, and two resetting coils, one for each magnetic switch, connected in circuit with the last mentioned vehicle electromagnet. 70 75

51. In a train control system, the combination with a roadside magnetic element and a roadside inductorium, means for controlling the direction of flow of induced current through one of said inductoriums, a relay carried by a moving vehicle, a source of electrical energy for controlling the same, train controlling means under the operation of the relay, a magnetic switch normally holding the circuit with the relay closed and adapted to be opened when passing over the roadside magnetic element, a vehicle carried inductorium disposed to control the said magnetic switch to return the same to closed position when passing in inductive relation to the roadside inductorium, and a resetting circuit including the source of electrical energy, a hand operated switch and a coil, the said coil being disposed in influencing relation to the magnetic switch to close the same after the train controlling means has been operated to stop the train. 80 85 90 95 100

52. In a train control system, the combination with a roadside magnetic element and a roadside inductorium, means for controlling the direction of flow of induced current through one of said inductoriums, a relay carried by a moving vehicle, a source of electrical energy for controlling the same, train controlling means under the operation of the relay, a magnetic switch normally holding the circuit with the relay closed and adapted to be opened when passing over the roadside magnetic element, a coil disposed in inductive relation to the magnetic switch, an inductorium in circuit therewith and disposed to pass in inductive relation with the roadside inductorium after said switch has been moved by the magnetic element to reset the said switch into closed position, and a resetting circuit including the source of electrical energy, a hand operated switch, and a coil, the said coil being disposed in influencing relation to the magnetic switch to close the same after the train controlling means has been operated to stop the train. 105 110 115 120

53. In a train control system, the combination of a permanent magnet disposed along the roadside, two electromagnets also disposed along the roadside and connected in circuit to each other, roadside means for controlling the direction of flow of induced cur- 125 130

- rent from one of the latter to the other, roadside means for opening the circuit between the two electromagnets, vehicle carried means including train controlling means, a source 5 of electrical energy, a magnetically controlled switch for controlling the train controlling means, said switch being adapted to be moved to open position when passing the permanent magnets, two electromagnets, one in circuit 10 with the source of electrical energy and the other in circuit to control said magnetic switch, whereby when the two last mentioned electro-magnets pass in inductive relation to the roadside electro-magnets the magnetic switch will be controlled thereby relative to 15 the direction of flow of the induced current from the source of electrical energy of the vehicle through all of the electromagnets, and a resetting circuit including the source of 20 electrical energy, a hand operated switch and coil, the said coil being disposed in influencing relation to the magnetic switch to close the same after the train controlling means has been operated to stop the train.
- 25 54. In a train control system, the combination with a permanent roadside magnet, two electromagnets connected in a partial circuit and disposed along the roadside, pole changing means in said circuit controlled 30 from the roadside, means for opening said partial circuit controlled from the roadside, a vehicle carried source of electrical energy, two relays in circuit therewith, train controlling means under the influence of said re- 35 lays, two magnetic switches normally closed for controlling the respective relays, said switches being adapted to be opened when passing the permanent magnet, two electromagnets, one in circuit with the source of 40 electrical energy and both disposed to pass in inductive relation to the roadside electromagnets whereby an induced current is transmitted from the electromagnet connected with the source of electrical energy through 45 the roadside electromagnets to the remaining vehicle electromagnet, two resetting coils, one for each magnetic switch, connected in circuit with the last mentioned vehicle elec- 50 tromagnet, and a resetting circuit including the source of electrical energy, a hand operated switch and a coil, the said coil being disposed in influencing relation to one of the magnetic switches to close the same after the train controlling means has been operated to 55 stop the train.
55. In a train control system, the combination with a permanent roadside magnet, two electromagnets connected in a partial circuit and disposed along the roadside, pole 60 changing means in said circuit controlled from the roadside, means for opening said partial circuit controlled from the roadside, a vehicle carried source of electrical energy, two relays in circuit therewith, train controlling 65 means under the influence of said re-
- lays, two magnetic switches normally closed for controlling the respective relays, said switches being adapted to be opened when passing the permanent magnet, two electromagnets, one in circuit with the source of electrical energy and both disposed to pass in inductive relation to the roadside electromagnets whereby an induced current is transmitted from the electromagnet connected with the source of electrical energy through the roadside electromagnets to the remaining vehicle electromagnet, two resetting coils, one for each magnetic switch, connected in circuit with the last mentioned vehicle electromagnet, and a speed circuit controller under the influence of one of the relays and disposed to be connected in circuit with the train controlling means when the polarity of the partial circuit has been changed due to a caution condition and for regulating the speed of the train after such actuation. 70
56. In a train control system, the combination with a permanent roadside magnet, two electromagnets connected in a partial circuit and disposed along the roadside, pole changing means in said circuit controlled from the roadside, means for opening said partial circuit controlled from the roadside, a vehicle carried source of electrical energy, two relays in circuit therewith, train controlling means under the influence of said relays, two magnetic switches normally closed for controlling the respective relays, said switches being adapted to be opened when passing the permanent magnet, two electromagnets, one in circuit with the source of electrical energy and both disposed to pass in inductive relation to the roadside electromagnets whereby an induced current is transmitted from the electromagnet connected with the source of electrical energy through the roadside electromagnets to the remaining vehicle electromagnet, two resetting coils, one for each magnetic switch, connected in circuit with the last mentioned vehicle electromagnet, and signals indicating clear, caution and danger, under the influence of said relays. 75
57. In combination, vehicle carried mechanism, means including roadside mechanism for influencing the vehicle carried mechanism in the movement of the vehicle over a roadway for producing a given condition, and means for influencing said vehicle carried mechanism for producing a different condition including a vehicle energy receiving inductor, a roadside energy transmitting inductor, and a vehicle source of energy for said receiving and transmitting inductors. 80
58. In combination, vehicle carried mechanism, means including roadside mechanism for influencing the vehicle carried mechanism in the movement of the vehicle over a roadway for producing a given condition, and means for influencing the vehicle carried 85

mechanism for producing a different condition including vehicle energy transmitting and receiving inductors, a source of energy therefor, and track energy receiving and transmitting inductors cooperating therewith.

59. In combination, vehicle carried mechanism, means including roadside mechanism for periodically influencing the vehicle carried mechanism in the movement of the vehicle over a roadway for producing a given condition, and means for periodically influencing the vehicle carried mechanism for producing a different condition including vehicle energy transmitting and receiving inductors, a source of energy therefor, and track energy receiving and transmitting inductors cooperating therewith.

60. In combination, vehicle carried mechanism including a normally closed operating circuit, means including roadside mechanism for opening the circuit in the movement of the vehicle, and means for determining the operation of said opened circuit including a vehicle energy receiving inductor, a roadside energy transmitting inductor, and a vehicle source of energy for said energy receiving and transmitting inductors.

61. In combination, vehicle carried mechanism and provisions for controlling the same, said provisions including a roadside energy transmitting inductor, a vehicle energy receiving inductor, means including a vehicle source of energy for energizing said roadside transmitting inductor, and roadside mechanism for governing the direction of flow of energy to said roadside transmitting inductor.

62. In combination, vehicle carried mechanism and provisions for controlling the same, said provisions including a roadside energy transmitting inductor, a vehicle energy receiving inductor, means including a source of energy for energizing the said transmitting inductor, and roadside means operative for transmitting, modifying and inhibiting the transmission of such energy to said transmitting inductor.

63. In a train control system, vehicle carried mechanism, means comprising roadside mechanism for influencing the same in the movement of the vehicle to produce a tripping effect therein, and means for determining the state of operation thereof when the same is tripped including cooperative vehicle and roadside inductors, and a vehicle source of energy for operating the said inductors.

64. In a train control system, vehicle carried means operative to produce a predetermined effect, roadside means for producing such effect, and means for modifying such effect including a vehicle carried impulse receiving inductor, a roadside impulse transmitting inductor with which said receiver is

cooperable, and a source of electrical energy on the vehicle for energizing the roadside impulse transmitting inductor.

In testimony whereof I affix my signature.
